UNITED STATES PATENT OFFICE.

FRANCIS J. REILLY, OF NEW YORK, N. Y.

INFANT'S BATH CHAIR.

1,414,897.

Specification of Letters Patent.

Patented May 2, 1922.

Application filed May 14, 1921. Serial No. 469,433.

To all whom it may concern:

Be it known that I, FRANCIS J. REILLY, a subject of the King of Great Britain, and a resident of the city of New York, borough 5 of Manhattan, in the county and State of New York, have invented new and Improved Infants' Bath Chairs, of which the following is a full, clear, and exact description.

This invention relates to bath chairs particularly adapted for infants and has for 10 an object to provide an improved construction which may be readily set into a tub or receptacle of any kind for supporting a child a short distance above the bottom thereof 15 and at the same time allowing a comfortable posture to be assumed by the child.

Another object of the invention is to provide a bath chair for an infant which will 20 present a seat and a compartment or cavity for receiving part of the head in order to hold the infant properly on the chair easily 25 during the bathing operation.

A still further object of the invention is to provide a bath chair for infants which 25 may be readily folded and which is so formed that part may be removed for cleaning at any time.

In the accompanying drawing—

Figure 1 is a perspective view of a bath 30 chair disclosing one embodiment of the invention.

Figure 2 is a perspective view of the chair shown in Figure 1, the same being in a folded condition.

35 Figure 3 is a fragmentary edge view of one of the side bars of the chair shown in Figure 1, the same being on an enlarged scale.

Figure 4 is an enlarged detail fragmentary 40 sectional view through Figure 1 on line 4—4.

Referring to the accompanying drawing by numerals, 1 and 2 indicate the upright bars of the chair, said bars being pivotally 45 mounted at 3 and 4 to seat bars 5 and 6 which also carry legs 7 and 8 pivotally mounted on the front bar 9. The bars 1 and 2 have extensions 10 and 11 which act as supporting legs in connection with the 50 legs 7 and 8 to which they are tied by suitable links 12 and 13. This arrangement permits the parts to be readily folded as shown in Figure 2. In order to prevent folding when the chair is in use, brace rods 14 and 55 15 are pivotally connected to the rear end of the bars 5 and 6 while the upper ends

are bent to form hooks 16 projecting into the respective slots 17 and 18 and a pair of notches 19 is associated with each slot so as to receive the bent over end 16 of the 60 respective brace bars. In case the back is to be more inclined than that shown in Figure 1 the ends 16 are shifted to the upper notches 19. When it is desired to fold the chair the ends 16 are shifted up to a point 65 near the upper ends of the slots 17 and 18 as shown in Figure 2. A suitable bracing rod 20 is connected to the rear end of the bars 5 and 6.

In order that the framework just described 70 may provide a proper support for the infant, a flexible seat 21 is provided which merges into a back section 22. The material of which the seat 21 and the back section 22 are formed is preferably cloth, as for instance, an ordinary Turkish towel cloth, said cloth being of such a length as to be folded over the front bar 9 and the top bar 23. A suitable row of fastening means, as for 75 instance, buttons 24 are provided at the top and a single row of buttons or other fastening means 25 are provided at the bottom. These buttons interlock with the cloth by being inserted through suitable button holes as illustrated in Figure 4. By this construction and arrangement the body or central 80 part of the chair may be removed for washing or any other purpose.

In forming the back section 22 a special 85 pocket or recess 26 is provided which is 90 designed to receive part of the head of the infant and which thereby presents means which will prevent the infant from readily falling out of the chair. This extra concave or depressed section 26 may be made 95 in any desired manner, a convenient method being shown in Figure 4 wherein an extra piece 27 is stitched by suitable stitching 28 to the body of section 22, which section is made double and consequently permits the 100 edge of the member 27 to be inserted therebetween. This will prevent any considerable ridge or lump to be formed.

In operation the chair is set up or unfolded so that it will present an arrangement substantially as shown in Figure 1. The height of the seat section 21 is a very short distance from the bottom of the tub, as for instance, a few inches. After the parts have been arranged as shown in Figure 1 110 and the chair deposited in the tub the child is seated on the section 21 and is allowed

to recline so that part of its head will fit into the recess section 26. The child may pass directly to the front or may face either side of the chair and yet retain part of its head in the recess 26 which will prevent any accidental falling and consequent injury. This shifting of position will permit the person bathing the child to readily bathe all parts of the body.

10 What I claim is:—

1. A bath chair for infants comprising a rectangular frame acting as a seat frame, a pair of uprights acting as a back frame, a rod connecting said uprights at one end, means for connecting said uprights to said seat frame near the opposite end, a pair of legs pivotally connected with said seat frame at their front end, a link at each side of

said seat frame and parallel thereto pivotally connected with said legs and with 20 said back frame, a rod connecting the parts of the front end of said seat frame, a flexible cloth body connected with said rod and with the rod connecting the back frame whereby a combined seat and back is formed, said back 25 being formed with a depression for receiving the infant's head while sitting on the seat, and adjustable means for connecting the seat frame and the back frame.

2. In a bath chair for infants, a flexible 30 cloth body forming a seat and back structure, said back structure having a concave portion merging into the body for receiving part of the head of the infant when the device is in use.

FRANCIS J. REILLY.
